UNITED STATES PATENT OFFICE

125,314

DESIGN FOR A FLUORESCENT WATER-
PROOF LIGHT FIXTURE

Leo Ralph Proulx, Los Angeles, Calif.

Application September 28, 1940, Serial No. 95,498

Term of patent 7 years

To all whom it may concern:

Be it known that I, Leo Ralph Proulx, a citizen of the United States, residing at Los Angeles, in the county of Los Angeles and State of California, have invented a new, original, and ornamental Design for a Fluorescent Waterproof Light Fixture, of which the following is a specification, reference being had to the accompanying drawing, forming part thereof.

Fig. 1 is a perspective view of the fluorescent waterproof light fixture, showing my new design.

Fig. 2 is a section on the line 2—2 of Figure 1.

I claim:

The ornamental design for a fluorescent waterproof light fixture, as shown.

LEO RALPH PROULX.
